UNITED STATES PATENT OFFICE.

JAMES NUTTALL, OF BURY, ENGLAND.

ROTARY STEAM-JOINT.

955,097.

Specification of Letters Patent. Patented Apr. 12, 1910.

Application filed January 21, 1910. Serial No. 539,255.

To all whom it may concern:

Be it known that I, JAMES NUTTALL, a subject of the King of Great Britain, of Park View, Walmersley Road, Bury, in the county of Lancaster, England, have invented a new and useful Improved Rotary Steam-Joint, of which the following is a specification.

My invention relates to apparatus where-
10 in cylinders, or the like, are heated by
means of steam admitted into the cylinder,
or the like, and the water of condensation
passes out through a hollow journal, or
hollow journals, and through a port, or
15 ports, in a head, or heads, which is, or are,
hollow and carried by, and in communica-
tion with, the said hollow journal, or jour-
nals, and controlled by covers acting as
bearing pieces for the said head, or heads,
20 and having the inlet and outlet passages
connected therewith.

The principal object of my present in-
vention is to so arrange such apparatus that
it acts as a steam trap, preventing waste of
25 steam and insuring a very efficient discharge
of the water of condensation, as well as pre-
senting the advantages of external bearings
which at once show any leakage of steam
which may occur and being capable of being
30 tightened up while the apparatus is in op-
eration and also of acting as a safety valve
as in the case of the devices described in the
aforesaid specifications of my prior applica-
tions for Letters Patent.

35 According to my present invention I ar-
range the port, or ports, in the rotatable
head, or heads, for the outlet of water of
condensation so that the said port, or ports,
is, or are, in communication with the water
40 outlet passages only at intervals. During
the periods between such intervals the said
port is, or ports are, closed by coming oppo-
site a solid part of the cover, or covers, and
the steam will thus be trapped. I provide
45 a receiver of ample capacity to hold the
water ejected at each revolution, the outlet
pipe (or pipes) leading from this receiver
being preferably made of small diameter to
check the flow of water to the main exhaust
50 pipe, or passage, so that the water outlet
port, or ports, in the hollow head, or heads,
will pass onto the solid portion of the cover,
or covers, before the whole of the water has
passed from the said receiver and thus pre-
55 vent undue rush of steam from the cylinder,
or the like.

The accompanying drawing illustrates ar-
rangements in accordance with this inven-
tion.

Figure 1 shows the device in longitudinal 60
section with the inlet and outlet in the re-
spective covers at one end of the cylinder,
or the like, (parts only of the ends of which
are shown). Fig. 2 is a transverse section,
on the line A, B, Fig. 1. Fig. 3 shows one 65
of the covers at one end provided with the
water outlet arrangement, the steam inlet
being through one of the covers at the other
end of the cylinder, or the like. Fig. 4
shows the steam inlet and the water outlet 70
arrangements both in connection with one of
the covers at one end of the cylinder, or the
like.

At one end of the cylinder, or the like, is
(in the arrangement Fig. 1) a hollow jour- 75
nal 1 and fixed to this is the hollow stem 2
carrying the hollow head 3. The covers 4
and 5 act as bearing pieces for the said head
3. The steam inlet pipe 6, passes through
the cover 5. The water outlet port 14 in 80
the hollow head 3 extends only for a short
distance around the hollow head so that
communication between the interior of the
cylinder, or the like, and the outlet pipe 7,
is established only at intervals as herein- 85
before explained. The chamber 15 in the
cover 4 constitutes the aforesaid receiver
for retaining a body of escaping water as
aforesaid. The outlet pipe 7, may be pro-
vided with a tap 16 to regulate the speed of 90
outflow. I do not limit myself to the precise
length of the port 14, but in the drawing I
have shown it as extending around about
one quarter of the circumference of the hol-
low head 3, so that, in this case, during each 95
half rotation, the port 14 will be entirely
closed, and during the other half rotation,
it will be gradually opening and closing as
the water is being passed into the re-
ceiver 15. 100

Fig. 3 shows the arrangement applied so
that steam enters at one end of the cylin-
der, or the like, and the water leaves at
the other end. The parts which correspond
with those shown in Figs. 1 and 2 are 105
marked with the same reference numerals,
the steam entering by the pipe 6, and the
cover 5 at one end and the water leaving by
the port 14 and receiver 15 in, and pipe 7
attached to, the cover 5 at the other end. 110

Fig. 4 shows an arrangement in which
the steam inlet, and water outlet, are both

in connection with one of the covers at one end of the cylinder, the other cover acting simply as a support to enable the first named cover to be held in proper position to make 5 a good joint. The parts are marked with the same reference numerals as are used to denote corresponding parts in the other figures. The steam inlet and water outlet arrangements are in connection with the 10 cover 5 and the cover 4 simply acts as a support.

If desired, the arrangements Figs. 1 and 4 may be used at each end of the cylinder, or the like, and the water be taken up and 15 expelled toward each end from the mid part of the cylinder, or the like.

The covers 4 and 5, in all the modifications illustrated, are connected by bolts and nuts (preferably with the intervention of 20 springs) the holes shown at 17 Fig. 2 being for the reception of these bolts.

Lubricating cups and stems are shown at 18 to lubricate the bearing faces of the covers and hollow head.

I do not limit myself to the heads 3 being 25 spherical, as they may be of other shape which will allow of rotation and of tightening up the bearing parts.

What I claim is:—

1. In a rotary joint of the character described, a hollow rotary stem having an outlet port, in combination with a bearing for

said stem having a discharge port adapted to communicate with said outlet port during only portion of the revolution of said hollow 35 stem, whereby the latter acts as a trap during the remainder of its revolution.

2. In a rotary joint of the character described, a hollow rotary stem provided with a hollow head having an outlet port, in combination with a bearing for said head, having a discharge port adapted to communicate with said outlet port during only portion of the revolution of said head, whereby the latter acts as a trap during the remainder 45 of its revolution.

3. In a rotary joint of the character described, a hollow rotary stem having an outlet port, in combination with a bearing for said stem having a discharge port adapted 50 to communicate with said outlet port during only portion of the revolution of said hollow stem, whereby the latter acts as a trap during the remainder of its revolution, together with a chamber of relatively large 55 capacity into which said discharge port opens, as and for the purpose described.

In testimony whereof I have signed my name to this specification in the presence of two subscribing witnesses.

JAMES NUTTALL.

Witnesses:

WILLIAM HENRY SMITH,
JOHN RIDING.
